DESIGN FOR A CLASP FOR JEWELRY

Alfred Philippe, Scarsdale, N. Y., assignor to Trifari, Krussman & Fishel, Inc., New York, N. Y.

Application December 30, 1948, Serial No. 150,452

Term of patent 7 years

(Cl. D45—4)

To all whom it may concern:

Be it known that I, Alfred Philippe, a citizen of the United States of America, residing in Scarsdale, county of Westchester, and State of New York, have invented a new, original, and ornamental Design for a Clasp for Jewelry, of which the following is a specification, reference being had to the accompanying drawing, forming part thereof.

Fig. 1 is a plan view of a clasp for jewelry, showing my new design.

Fig. 2 is an edge view thereof.

Fig. 3 is a plan view illustrating the clasp in separate position.

Fig. 4 is an edge view of Figure 3.

I claim:

The ornamental design for a clasp for jewelry, substantially as shown.

ALFRED PHILIPPE.
